ATOMIZER

Yoshio Ota, No. 1, 152 5-chome, Sugamo, Toshima-ku,
Tokyo, Japan

Filed June 16, 1964, Ser. No. 80,417

Term of patent 14 years

(Cl. D58—9)

FIG. 1 is a rear elevational view of an atomizer, showing my new design;

FIG. 2 is a side elevational view thereof;

FIG. 3 is a front elevational view thereof; and

FIG. 4 is a top plan view thereof.

I claim:

The ornamental design for an atomizer, as shown.
